AUTOMATIC OIL RETURN SYSTEM FOR
TURBINE PUMPSJames M. Hait, Los Angeles, Calif., assignor to
Food Machinery Corporation, a corporation of
Delaware

Application March 27, 1937, Serial No. 133,372

11 Claims. (Cl. 103—102)

This invention relates generally to deep well turbine pumps such as are used in pumping water wells for domestic and industrial purposes. The invention is particularly in the provision of improved means for controlling the lubricant used to lubricate the line shaft bearings of the pump so that the lubricant does not enter either the well water or the water being pumped to the surface of the ground. The invention herein described is an improvement over the general type of apparatus set forth in my Patents No. 2,041,999 on Oil return system for deep well turbine pumps and No. 2,068,175 on Means for lubricating a deep well pump, and over the apparatus set forth in my co-pending application for Letters Patent on Lubricating system for vertical pump shaft, Serial No. 18,820.

This invention is adapted to be embodied in a deep well turbine pump of the type utilizing the so-called "drip method" of delivering lubricant to the line shaft enclosing tubing. The primary object of the invention is to provide means for automatically accumulating the lubricant which has traversed the line shaft enclosing tubing and the line shaft bearings in the region of the impellers of the pump out of contact with the water in the well and in the pump. It is also an object to provide means for automatically separating the water content of the lubricant which becomes emulsified in its passage through the bearings, and means for automatically returning the lighter components of the emulsion, or in other words, a clean lubricant, to the surface for re-use. In accomplishing this object it is a further object of this invention to utilize the pressure of the fluid being pumped to raise the separated lubricant to the surface.

In connection with the accumulation and separation of the emulsified lubricant which has traversed the line shaft enclosing tubing and line shaft bearings, it is an object of this invention to provide fully automatic means for accomplishing this which only requires an occasional stopping of the pump for a short period of time for the successful operation of the apparatus. Invariably, industrial and municipal installations of turbine pumps of the type, in which the invention is adapted to be embodied, operate with a daily or weekly interruption. Some installations operate longer without interruptions and the invention is designed to be adaptable to operate in connection with pumps operating under such conditions.

Finally, it is an object of this invention to provide means for accomplishing the objects out-

lined above which consists of a minimum of parts, none of which continuously operate, and which may be readily added to a standard turbine pump or readily built into a standard pump at the time of manufacture.

These objects are attained by the apparatus set forth in the accompanying drawings, which it is to be understood are for illustrative purposes only, and in which:

Fig. 1 is an elevational view with parts broken away showing a turbine pump assembly equipped with a preferred embodiment of the invention.

Fig. 2 is a fragmentary sectional elevation of the accumulator and separator chambers shown in Fig. 1 of the drawings.

Fig. 3 is a sectional plan view on line 3—3 of Fig. 2.

Fig. 4 is a sectional plan view on line 4—4 of Fig. 2.

Fig. 5 is a diagrammatic view of a system for directly returning the lubricant to the top of the line shaft enclosing tubing.

Fig. 6 is an enlarged sectional elevation of the valve employed in the accumulator and separator chambers.

Fig. 7 is a sectional elevation of another valve adaptable for use with the accumulator and separator chambers.

Fig. 8 is a fragmentary sectional elevation of a modified form of the invention wherein the accumulator and separator chambers surround the lower end of the line shaft enclosing tubing inside of the fluid delivery pipe.

Fig. 9 is a fragmentary sectional elevation of the annular partition separating the upper and lower chambers showing a modified form of the invention which does not require a valve.

Referring to the drawings, reference numeral 11 generally indicates a pump head assembly of conventional type which includes a motor housed in the upper portion 12 of the assembly and a discharge conduit 13. The motor in the pump head assembly is in driving engagement with a line shaft 14 which extends into the well 15 and on which are mounted the conventional impellers, 16 one impeller unit being shown housed in the bowl assembly 16. Surrounding the line shaft is a line shaft enclosing tubing 17 in which are mounted in spaced relationship the ordinary line shaft bearings, two of which are indicated by reference numerals 18 and 19. Surrounding the shaft enclosing tubing 17 and spaced therefrom is a fluid delivery pipe 20 connected at its upper end to the pump head assembly 11 and in open communication with the discharge conduit 13. It

is connected at its lower end to the bowl assembly 16 in the well. The line shaft 14 extends through a fitting generally indicated by reference numeral 21 at the top of the shaft enclosing tubing 17. 5 The fitting 21 provides a chamber 22 into which the lubricant is fed drop by drop at a sufficient rate to effectively lubricate the line shaft bearings. This lubricant is stored in a chamber 23 from which it is conducted to the chamber 22 by 10 means of a pipe 24 which includes a dripper valve 25 for the regulation of the flow of lubricant through the pipe.

For accomplishing the objects of accumulating and separating the component parts of the 15 water emulsified lubricant which has traversed the line shaft and line shaft bearings, a casing 28 is provided which extends above and preferably below the bowl assembly 16. This casing comprises an upper section 29 which is secured 20 in spaced relationship to the delivery pipe 20 by means of annular plate 30 to which it is welded or otherwise secured. At its lower end the upper section 29 is threaded on an annular plate 31 welded to the delivery pipe 20. The plate 25 31 forms the lower closure of an upper chamber 32 formed by the casing section 29, delivery pipe 20, plate 30 and plate 31. Threaded onto the plate 31 is a lower section 34 which forms what may be termed an open-ended lower chamber 35 surrounding the delivery pipe 20 and bowl assembly 16 and the intake portions 36 of the pump. This lower chamber 35 is in open communication with the well at its lower end which is designated by reference numeral 34. 30

35 For the purpose of providing the conventional communication from the interior of the shaft enclosing tubing 17 to the chamber 35, a by-pass 37 is provided just below the line shaft bearing 19. This by-pass is formed in a rib 38. Below 40 the bearing 19 an annular chamber 39 is provided with which the inlet of the by-pass 37 communicates. Below this chamber is a bearing 40. Interposed between the bearing 40 and the impeller 41 is provided sealing means, generally indicated by reference numeral 42, to restrict passage of fluid through bearing 40.

It is evident that with this construction the pressure in the chamber 35, since it is in open communication with the well, is substantially the 45 same as the static head of the water in the well. By reason of this it can be seen that the lubricant which has traversed the line shaft enclosing tubing and passed down through bearings 18 and 19 may escape from the shaft enclosing tubing into the chamber 35 by means of the by-pass 37 after sufficient amount has accumulated in the shaft enclosing tubing to counterbalance the static head of water in the well. In this connection there is no tendency for the fluid to 50 continue downwardly through bearing 40 inasmuch as the pressure at the lower end of the sealing means 42 is greater (during operation of the pump) than is the pressure at the upper end of bearing 40. Thus if there is any flow of fluid 55 through bearing 40 it is an upward flow which prevents any lubricant from working down through this bearing and into the pumped fluid stream.

The lubricant which has passed down through 60 the shaft enclosing tubing and out through the by-pass 37 is discharged into the lower chamber 35, the lighter components of the emulsified lubricant rising to the upper portion of the chamber below the plate 31 during the operation 65 of the pump. It is thus apparent that the emul-

sified lubricant is given opportunity to separate, that is, the oil separates from the water, while it is in the lower chamber.

To permit passage of the lubricant accumulated in the upper portion of the lower chamber 35 into the upper chamber 32 above it, the annular plate 31 is provided with a threaded opening 31' in which is threaded a valve generally indicated by reference numeral 45, which is designed to remain open only when the pressure 10 in chamber 35 is equal to or greater than the pressure in chamber 32. During the operation of the pump the pressure in chamber 32 is kept at a point substantially equal to the pressure of the pumped fluid inside the delivery conduit 20 15 by the provision of an opening or port 20' in the delivery pipe. Thus during the operation of the pump the pressure in chamber 32 is considerably higher than the pressure in chamber 35 (which is at substantially well pressure) and thus keeps 20 the valve 45 in closed position preventing the passage of any fluid from chamber 35 to chamber 32.

The upper end of the chamber 32 is provided 25 with a pipe 46 for delivering lubricant accumulated in the chamber 32 to the surface of the ground. This pipe has been shown as discharging into a container 47. A valve 46' is positioned at a suitable point in the pipe 46 for controlling passage of fluid therethrough. The container 47 is connected to the lubricant chamber 23 in the pump head assembly 11 by means of a pipe 48 suitably valved at 48'. The container 47 which is adapted to act as a separating chamber is provided with an outlet pipe 49 35 at the bottom, which has a valve 49'. This pipe is for the purpose of draining water from the container.

In the operation of the device the lubricant is 40 fed into the top of the line shaft enclosing tubing 17 and flows downwardly through bearings 18 and 19 and into the space 39, it becoming emulsified in its passage. From this point the lubricant, after a sufficient amount of it has accumulated to counterbalance the static head of the water in the well, passes through the by-pass 37 and into chamber 35 which is filled with water due to the fact that it is in open communication with the well at its lower end. The entire casing 28, in this connection, is situated 45 below the level of the water in the well. When the lubricant reaches the outlet of by-pass 37 it flows upwardly in chamber 35 and the lighter components accumulate in the upper portion of the chamber immediately below the plate 31. 50 While the well is being pumped the pressure in chamber 32 keeps the valve 45 closed and thus prevents escape of the lubricant from the chamber 35. While the lubricant remains in chamber 35 it has an opportunity to separate into its 55 component parts of oil and water, the oil gathering at the top and displacing the water from that portion of the chamber.

When the pump is stopped the pressure in chamber 32 becomes the same as that in chamber 35, due to the fact that the pressure of the fluid inside of the delivery pipe diminishes to the well pressure. This equalization of the pressure on both sides of the plate 31 permits the valve 45 to open and thereby permits the accumulated partially separated lubricant in the top portion of the chamber 35 to rise through the valve 45 and rise in chamber 32 to the top thereof, displacing the water which in turn flows through ports 20'. When the pump is again put 75

in operation the pressure in the chamber 32 is raised to that of the fluid inside of the delivery pipe 20. This pressure closes valve 45 and increases as the water rises in the conduit pipe until it is sufficient to raise the accumulated lubricant in the upper portion of the chamber through pipe 46 up to the surface of the ground and into the container 47, provided valve 46' has been opened and providing the pressure at discharge 13 is sufficient to raise the oil in pipe 46 to the elevation necessary to enter the top of container 47. If the water is discharged at the surface a valve or restriction may be required in discharge 13, although in most cases the column friction loss will supply the liquid differential. The valve 46' may be opened wide and left that way until the pipe begins to deliver water at its outlet or it may only be cracked and thus allow only as much lubricant to be delivered to the 20 surface as is being fed into the shaft enclosing tubing at the top thereof.

In this connection chambers 32 and 35 are constructed of sufficient size to accommodate the amount of lubricant which might accumulate in 25 them during the ordinary period of operation of the pump between shut downs. The section 34 of the casing is shown extending considerably below the outlet of the by-pass 37 so as to prevent any possibility of the lubricant escaping into 30 the well.

In Fig. 5 is shown another manner in which the lubricant may be returned to the top of the shaft enclosing tubing. The lubricant return pipe 46 in this construction leads directly to the 35 dripper valve 25 and is controlled by a valve 52. Between the valve 52 and the chamber 32 is a drain pipe 53 provided with a valve 54, by means of which samples of the fluid being raised through pipe 46 may be drawn off. The lubricant storage 40 chamber 23 in the pump head assembly is connected to the dripper valve by pipe 55 which is controlled by valve 56. The dripper valve 25 is connected to the chamber 22 at the top of the shaft enclosing tubing by the pipe 24.

The construction shown in Fig. 5 permits a closed automatic lubricating system after the system has become saturated with lubricant. When the pump is first installed and before such 45 time as sufficient lubricant has passed down through the shaft enclosing tube and out into the separating chambers and is in condition to be raised to the surface, the lubricant may be supplied to the top of the shaft enclosing tubing by means of the pipe 55 communicating with the 50 reservoir 23. During this initial operation of the pump the valve 56 would be open and valve 52 closed. After the pump has been in operation a sufficient time for lubricant to have passed down the shaft enclosing tubing and accumulated in the upper portion of the top accumulator chamber the valve 56 is closed and the valve 52 opened, thus permitting the lubricant being raised to the surface through pipe 46 to be delivered directly back to the top of the shaft enclosing 55 tubing. It may be necessary to first open valve 54 and permit escape of any water which may be in pipe 46 before opening valve 52 to permit the lubricant to flow to the dripper valve.

In Fig. 6 is shown the construction of valve 70 45 which is mounted in the opening 31' in the plate 31. A nipple 58 is threaded into the opening 31' and carries a short tube 59 which is threaded into the upper end of the nipple. Threaded on the upper end of the tube 59 is a 75 valve comprising a valve body 60 which has a

passage 61 which is in open communication at its lower end with chamber 35 through the tube 59 and nipple 58 and terminates at its upper end in a valve seat 62. A valve spring 63 is mounted by means of screws 64 on the valve body 60 and is adapted to remain in the position shown in Fig. 6, when the pressure of the fluid in the valve passage is greater than or equal to the pressure in the region of the closure member. Mounted on the outer end of the valve spring 63 is valve 10 closure member 65 which is preferably formed of an oil and water resistant material. This valve closure member 65 engages the valve seat 62 when the pressure in chamber 32 exceeds the pressure in the bore 61 which is in communication with 15 the chamber 35.

It should be apparent that this invention is not limited to the particular valve structure set forth in Fig. 6 and that the valve 45 is merely a typical form of valve structure which in practice 20 has been found to be satisfactory.

In Fig. 7 is illustrated another valve which is adaptable for use in the annular plate separating the upper and lower chambers. This valve generally indicated by reference numeral 68 comprises a valve body 69 having a central passageway 70 which terminates at its lower end in a threaded portion 71 adapted to be threaded on to a tube such as the tube 59 shown in connection with valve 45. The passageway 70 terminates at its upper end in a T outlet 72. Mounted on the upper end of valve body 69 is a valve cap 73 which is held in place on the valve body 69 by means of bolts 74. Between the top of valve body 69 and the inside of the top of the 35 valve cap 73 is a coil spring 75 which is surrounded by a water proof flexible encasement means 76. The lower end of the valve cap 73 has beveled edge 73' adapted to rest on the valve seat 77 formed on the valve body 69. This valve 40 seat 77 may be formed of "Duprene" or other suitable oil and water resistant material positioned in the annular groove 78.

In connection with the description of the chambers 32 and 35 it was pointed out that in 45 the ordinary operation of deep well turbine pumps the level of the water standing in the well would at all times be above the top of casing 28. However, to provide for the possibility of the water level receding to a point below the top of the casing 28 a stand pipe may be provided externally of the casing 28 which should be open at the top and thus provide a head of water on the lower open end of chamber 35 equivalent to the height of the stand pipe which 50 preferably should be the height of the casing 28 or slightly higher. Although this stand pipe might be embodied in the preferred form of the invention shown in Figs. 1 and 2, for purposes of illustration it has only been shown in 55 connection with a modified form of the invention illustrated in Fig. 8. Accordingly it will be more fully described with that form of the invention.

Fig. 8 illustrates a modified form of the invention wherein the accumulator and separator chambers are located immediately surrounding the lower end of the line shaft enclosing tubing and are within the delivery pipe. Referring particularly to Fig. 8 which is a fragmentary sectional elevation, reference numeral 80 indicates a bowl assembly. Mounted on the top of the bowl assembly is a case 81 on which is mounted a bearing 82 (equivalent to bearing 40, Fig. 2). Above the bearing the bore 83 is enlarged at 83' 70 75

and has threaded in its upper end another bearing 84 (equivalent to 19, Fig. 2). The delivery pipe, here indicated as 85 is threaded into the upper end of the case 81. A line shaft 86 extends downwardly through the apparatus and operates the impeller in the bowl assembly 80. Surrounding the line shaft 86 is the conventional shaft enclosing tubing 87 in which are mounted the spaced line shaft bearings, one of which is indicated at 88. Surrounding the shaft enclosing tubing at its lower end is a casing 89 which is formed of an upper section 90 and a lower section 91. An annular plate 92 divides the casing 89 into an upper chamber 93 and lower chamber 94. This plate 92 is apertured at 92' to accommodate a valve 95, similar to the valve shown and described in connection with the preferred form of the invention. Mounted in the upper end of the chamber 93 is a pipe 97, similar to pipe 46 of the preferred form and adapted to be connected at the surface as shown in Fig. 1. At the lower end of the shaft enclosing tubing 87 are apertures 87' which permit escape of accumulated lubricant into the chamber 94. The lubricant which has worked down through the shaft enclosing tubing and bearings therein may thus escape into chambers 94 through these openings and accumulate in the upper portion of the chamber just below the plate 92, dividing the upper and lower chambers.

During the operation of the pump the pressure in chamber 93 is maintained at substantially the pressure of the pumped fluid by means of an opening 90' in the upper section 90 of the casing 89. As in the preferred form of the invention, this pressure during operation of the pump serves to keep the valve 95 in a closed position, thus preventing any fluid from passing from chamber 94 to the chamber 93. When the operation of the pump stops the pressure in chamber 93 drops to that of well pressure permitting valve 95 to open. This allows the entrapped accumulated lubricant in the upper portion of chamber 94 to pass through the valve into the chamber 93 where it accumulates in the upper portion thereof.

It should be pointed out that at all times the pressure in chamber 94 is substantially that of the well pressure. This is accomplished by the provision of a by-pass 98 which communicates with the interior of the shaft enclosing tubing and which is in open communication with the well by virtue of the clearance existing between the shaft and the bearing 84.

To take care of the possibility that the water in the well might drop below the casing 89 and thus permit the lubricant from the shaft enclosing tubing to seep into the well water, a stand pipe 99 is mounted on the lower portion of the case 81 and extends upwardly a desirable distance above the casing 89. This stand-pipe is adapted to be open to the well at the top and will thus be filled when the water of the well is above it or by the high pressure leakage water escaping through bearing 82. When the water of the well recedes below the top of the stand-pipe, the stand-pipe retains a column of water sufficient to counterbalance the fluid in chambers 93 and 94, and thereby prevent the escape of any of the lubricant into the water of the well, since it is separated before it can leak through port 98.

In Fig. 9 there is illustrated a modified form of the invention which does not require a valve. The view shows a fragmentary section of the

plate separating the upper and lower accumulator and separator chambers. Reference numeral 101 indicates the casing means enclosing the chambers 102 and 103 and surrounding the delivery pipe 104. The chambers in this form of the invention occupy the same relative positions as are shown in Fig. 2. The annular plate separating the chambers designated by reference numeral 105 is provided with a very narrow passageway 106. The delivery pipe 104 is shown apertured at 104' but might preferably be apertured on the side opposite from the passageway 106. With this construction the lubricant escapes into chamber 103 as described in connection with the device shown in Fig. 2 and is prevented during operation of the pump from rising into chamber 102 by the pressure of the water in chamber 102 which is in open communication with the fluid delivery conduit. Thus, during operation of the pump a slight stream of water escapes through the passageway 106 into chamber 103, preventing passage of the lubricant upwardly therethrough. The lubricant accumulates in the chamber 103 below the plate 105 until the pump is stopped, when it may ascend into the upper chamber through the passage 106. When the pump is started the lubricant accumulated in the upper portion of the upper chamber may then be delivered to the surface of the ground in the manner above described in connection with the other forms of the invention. With this construction it is possible to eliminate the valve employed between the two chambers in the other forms of the device.

I claim as my invention:

1. For use in combination with a well turbine pump having a bowl assembly, a line shaft, a shaft-enclosing tubing adapted to receive a lubricant at its upper end, and a delivery pipe enclosing said tubing, a lubricant accumulator and separator means comprising: casing means forming a closed upper chamber and a lower chamber open to the well at a point below the well liquid level when the pump is operating, said lower chamber communicating with the interior of said shaft-enclosing tubing; said delivery pipe having a port in the region of the lower portion of said upper chamber to communicate said upper chamber with the delivery pipe, said port being below the liquid level in the upper chamber when the pump is not operating; conduit means connecting the upper portion of the upper chamber with the surface of the ground; and a normally open valve between said chambers adapted to be closed by the pressure in the upper chamber when the pump is operating.

2. For use in combination with a well turbine pump having a bowl assembly, a line shaft, a shaft-enclosing tubing adapted to receive a lubricant at its upper end, and a delivery pipe enclosing said tubing, a lubricant accumulator and separator means comprising: casing means surrounding said tubing in the region of the lower end of said tubing; partition means mounted between said tubing and said casing and cooperating with those elements to form closed upper and lower chambers; said tubing being apertured to provide communicating means between said lower chamber and the interior of said tubing; said casing means having a port in the region of the lower portion of said upper chamber to communicate said upper chamber with the delivery pipe, said port being below the liquid level in the upper chamber when the pump is not operating; by-pass means connecting the interior of said

tubing with the well; a normally open valve mounted on said partition means adapted to be closed by the liquid pressure in the upper chamber when the pump is operating; and conduit means connecting the upper portion of the upper chamber with the surface of the ground.

3. For use in combination with a well turbine pump having a bowl assembly, a line shaft, a shaft-enclosing tubing adapted to receive a lubricant at its upper end, and a delivery pipe enclosing said tubing, a lubricant accumulator and separator means comprising: casing means surrounding said tubing in the region of the lower end of said tubing; partition means mounted between said tubing and said casing and cooperating with those elements to form closed upper and lower chambers; said tubing being apertured to provide communicating means between said lower chamber and the interior of said tubing; said casing means having a port in the region of the lower portion of said upper chamber to communicate said upper chamber with the delivery pipe; by-pass means providing communication from the interior of said tubing to the exterior of said delivery pipe; a normally open valve mounted in said partition means adapted to be closed by the pressure in the upper chamber when the pump is operating; conduit means connecting the upper portion of the upper chamber with the surface of the ground; a stand-pipe surrounding said delivery pipe from a point below said by-pass means to a point above the top of said upper chamber, said stand-pipe being open to the well at its top and closed at the bottom.

35 4. For use in combination with a well turbine pump having a bowl assembly, a line shaft, a shaft-enclosing tubing adapted to receive a lubricant at its upper end, and a delivery pipe enclosing said tubing, a lubricant accumulator and separator means comprising: a housing below the top of said shaft-enclosing tubing forming a closed upper chamber and a lower chamber open to the well at a point below the well liquid level when the pump is operating, the lower portion of said upper chamber being in open communication with the interior of said delivery pipe at a point below the liquid level in the upper chamber when the pump is not operating; by-pass means connecting said lower chamber and the interior of said tubing; means for preventing lubricant in said lower chamber from entering said upper chamber when the pump is operating and for permitting such lubricant passage when the pump is not operating; and conduit means connecting the upper portion of the upper chamber with the surface of the ground.

50 5. For use in combination with a well turbine pump having a bowl assembly, a line shaft, a shaft-enclosing tubing adapted to receive a lubricant at its upper end, and a delivery pipe enclosing said tubing, a lubricant accumulator and separator means comprising: a housing below the top of the shaft-enclosing tubing forming a closed upper chamber and a lower chamber open to the well at a point below the well liquid level when the pump is operating, the portion of said housing forming a partition between said upper and lower chambers being provided with an opening to communicate said upper and lower chambers; by-pass means connecting said lower chamber and the interior of said tubing; said delivery pipe having a port in the region of the lower portion of the upper chamber to communicate said upper chamber with the interior of said delivery pipe, said port being below the liquid level in the upper chamber when the pump is not operating; and conduit means connecting the upper portion of the upper chamber with the surface of the ground.

55 6. For use in combination with a well turbine pump having a bowl assembly, a line shaft, a shaft-enclosing tubing adapted to receive a lubricant at its upper end, and a delivery pipe enclosing said tubing, an oil circulating system comprising: a housing below the top of the shaft-enclosing tubing forming a closed upper chamber and a lower chamber open to the well at a point below the well liquid level when the pump is operating; by-pass means connecting said lower chamber and the interior of said tubing; a normally open valve between said chambers closable by the pressure of the liquid in the upper chamber when the pump is operating; said upper chamber being in open communication with the interior of said delivery pipe near the lower end of said upper chamber and at a point below the liquid level in the upper chamber when the pump is not operating; and conduit means connecting the upper portion of the upper chamber with the top of said shaft-enclosing tubing.

7. For use with a well turbine pump having a bowl assembly, a line shaft, a shaft-enclosing tubing adapted to receive a lubricant at its upper end, and a delivery pipe enclosing said tubing, the combination of: a lubricant accumulator and separator having a closed upper chamber and a lower chamber open to the well at a point below the well liquid level when the pump is operating, said lower chamber being in open communication with the interior of said tubing, said upper chamber being in communication with the interior of said delivery pipe in the region of the lower end of the said upper chamber and at a point below the liquid level in the upper chamber when the pump is not operating; conduit means connecting the upper portion of the upper chamber with the surface of the ground; and means operable by the variation in pressure of the liquid in said delivery pipe for controlling the passage of lubricant from said lower chamber to said upper chamber.

8. For use in combination with a well turbine pump having a bowl assembly, a line shaft, a shaft-enclosing tubing adapted to receive a lubricant at its upper end, and a delivery pipe enclosing said tubing, a lubricant accumulator and separator means comprising: casing means surrounding said tubing in the region of the lower end of said tubing forming closed upper and lower chambers, the portion of said casing forming a partition between said upper and lower chambers being provided with an opening to communicate said upper and lower chambers; said tubing being apertured to provide communicating means between said lower chamber and the interior of said tubing; said casing means having a port in the region of the lower portion of said upper chamber to communicate said upper chamber with the delivery pipe, said port being below the liquid level in the upper chamber when the pump is not operating; and conduit means connecting the upper portion of the upper chamber with the surface of the ground.

9. For use in combination with a well turbine pump having a bowl assembly, a line shaft, a shaft-enclosing tubing adapted to receive a lubricant at its upper end, and a delivery pipe enclosing said tubing, a lubricant accumulator and separator means comprising: casing means below the top of said shaft-enclosing tubing forming

- 5 a closed upper chamber and a lower chamber, said upper chamber being in open communication with the interior of said delivery pipe in the region of the lower end of said upper chamber and at a point below the liquid level in the upper chamber when the pump is not operating; said lower chamber communicating with the interior of said tubing; means for preventing lubricant in said lower chamber from entering said upper 10 chamber when the pump is operating and for permitting such lubricant passage when the pump is not operating; and conduit means connecting the upper portion of the upper chamber with the surface of the ground.
- 15 10. For use in combination with a well turbine pump having lubricant supply means, lubricant escape means, and a delivery pipe, a lubricant accumulator and separator means comprising: casing means forming a closed upper chamber 20 and a lower chamber open to the well at a point below the well liquid level when the pump is operating, said lower chamber communicating with the lubricant escape means; communicating means between the lower portion of the upper 25 chamber and the interior of the delivery pipe, said means being at a point below the well liquid level when the pump is not operating; conduit means connecting the upper portion of the upper chamber with the surface of the ground; and means for 30 preventing lubricant in said lower chamber from entering said upper chamber when the pump is operating and for permitting such lubricant passage when the pump is not operating.

11. For use in combination with a well turbine pump having a bowl assembly, a line shaft, a tubing enclosing said shaft adapted to receive a lubricant at its upper end, and a delivery pipe enclosing said tubing, a lubricant accumulator and separator means comprising: by-pass means interposed between the interior of said tubing and the exterior of said pipe; an elongated casing surrounding said delivery pipe in the region of the outlet of said by-pass, said casing being closed 10 at the top and open at the bottom, the bottom of said casing being below the well liquid level when the pump is operating; a partition member located above said by-pass means connecting said casing and said delivery pipe and cooperating with those 15 members to form an upper and a lower separating chamber; said upper chamber being in open communication with the interior of said delivery pipe by means of an aperture in said delivery pipe opening into the lower portion of said upper 20 chamber, said aperture being below the liquid level in the upper chamber when the pump is not operating; communicating means between the upper portion of said lower chamber and said upper chamber; a valve controlling said communicating means and adapted to be closed when the pressure in said upper chamber exceeds the 25 pressure in said lower chamber; and a lubricant return conduit connecting the top of said casing with the surface of the ground. 30

JAMES M. HAIT.
